UNITED STATES PATENT OFFICE

AMOS K. KILGORE, OF DALLAS, TEXAS

NEWSPAPER DISPLAY RACK

Application filed August 3, 1928. Serial No. 297,295.

The present invention relates to improvements in racks and stands, and has reference more particularly to a device for holding and displaying newspapers, magazines, and other similar articles.

One of the important objects of the present invention is to provide a display rack of the above mentioned character that includes a support on which is arranged a series of gripping members so constructed as to permit a newspaper to be readily inserted or removed from between the adjacent gripping members, said gripping members being disposed in overlapping relation.

A further object is to provide a newspaper display rack of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawing, forming a part of this application and wherein like reference characters designate like parts throughout the several views:

Figure 1 is a side elevation of the display rack embodying my invention, in the same position for use.

Figure 2 is a front elevation of the rack for more clearly disclosing the construction of the gripping member, and

Figure 3 is a sectional view, taken approximately on the line 3-3 of Figure 1, looking downwardly.

In the drawing, wherein for the purpose of illustration is shown the preferred embodiment of my invention, the numeral 1 designates my improved display rack, the same comprising a rectangular shaped frame constructed of angle iron side bars 2 and 3 that are connected at their upper ends in parallel spaced relation by the cross bar 4, which is also of angle iron material. A cross strip 5 extends between the lower end portions of the angle iron side bars as clearly illustrated in Figure 2 of the drawing.

A longitudinally extending flat bar or strip

6 is disposed between the angle iron side bars 2 and 3, and the upper end of the longitudinal strip 6 is secured to the top cross piece 4, while the lower end of said longitudinally disposed strip is connected to the intermediate portion of the bottom cross strip 5 as clearly suggested in Figure 2 of the drawing.

For the purpose of supporting the frame in a slightly tilted vertical position, I provide the supporting legs 7, a pair of such legs being provided for cooperation with the respective angle iron side bars of the frame. These legs are pivotally connected at their upper ends to the upper portions of the respective side bars as at 8, and the lower ends engage the ground as do also the vertically disposed side bars 2 and 3, shown in Figure 1. The lower end portions of the supporting leg are connected together by a cross strip, shown at 10.

For the purpose of limiting the rearward swinging movement of the supporting legs with respect to the frame of the display rack, there is provided for association with each supporting leg and its adjacent side bar a pair of arms 11 and 12. These arms are pivotally connected together, at their inner opposed ends as at 13.

The outer end of the arm 11 is pivotally connected to the outer side of the respective angle iron side bar of the frame, while the outer end of the complementary arm is pivotally connected to the outer side face of the adjacent supporting leg and this is clearly shown in Figures 1 and 3 of the drawings.

By swinging the arms 11 and 12 upwardly, the supporting legs may be moved inwardly toward the frame of the rack to provide a compact structure that can be stored away when not in use, without occupying any considerable amount of space. When the display rack is to be used, the parts are disposed in the manner as shown in Figure 1.

Forming a salient part of the present invention is an improved newspaper gripping member, a series of such members being provided. Each of these gripping members which is denoted generally by the reference character 14 is formed from a single strand of spring wire, bent into substantially inverted

U-shaped formation, the arms 15 and 16 slightly converging toward each other, from the crown portion 17.

Each of the arms of each U-shaped gripping member is formed adjacent its end with a series of abutting loops, whereby to form the coiled spring units 18. The free ends of the arms of each U-shaped gripping member are disposed through suitable openings 19 provided therefor in the front side of the angle iron side bars of the frame and are then bent upwardly against the rear face of the front side of the respective angle iron side bar as shown at 20 in Figure 1, so that said U-shaped gripping members will be properly supported on the frame, and it will be observed that the gripping members are so arranged that the crown portion 17 engages the arms 15 and 16 of the next uppermost gripping member and the coil spring units 18 will retain the gripping members in engagement with the next adjacent gripping member, said coil spring units having a tendency to normally urge the gripping members inwardly toward the frame of the rack.

When the parts are arranged as shown in the drawings, a newspaper or other article may be readily inserted between any adjacent pair of gripping members and the lower edge of the paper will rest on the coil spring unit 18 and will be properly maintained and positioned on the rack and against displacement therefrom by reason of the coil spring unit tensioning or urging the gripping members against the frame.

The arrangement of the gripping members in overlapping relation will permit a variety of newspapers to be displayed on the rack, so that the upper portions of the several periodicals can be viewed without necessitating the removal of the periodical from the rack, except when purchasing the same.

The provision of a display rack of the above mentioned character enables the same to be constructed at a very low cost, and yet be strong and durable, and at all times positive and efficient in carrying out the purpose for which it is designed.

While I have shown the preferred embodiment of my invention, it is to be understood that various changes in the size, shape and arrangement of parts may be resorted to, without departing from the spirit of the invention or the scope of the appended claim.

What I claim as new is:

A device for holding and displaying newspapers and the like comprising a supporting frame including parallel spaced vertically disposed side bars, cross bars connecting said side bars, supporting legs hingedly connected at their upper ends to the respective side bars, hinged braces between the intermediate portions of the supporting legs and the respective side bars of the frames, a series of gripping members each of substan-

tially inverted U-shaped formation, the arms of each of said inverted U-shaped gripping members converging toward each other from the crown portion thereof, the arms being formed with coil spring units adjacent the free ends, the free ends of the arms disposed through openings formed in the side bars of the frame and disposed laterally against the inner face of the respective side bars, said U-shaped gripping members being disposed upon the frame in overlapping relation and adapted to receive the newspaper therebetween, the coil spring units of the respective gripping members providing a support for the paper, said coil spring units normally urging the respective U-shaped gripping members inwardly against one another for maintaining the papers securely therebetween.

In testimony whereof I affix my signature.

AMOS K. KILGORE.
